EMBORESSED LABEL CARD

David D. Fishback, 223 S. St. Francis,
Wichita, Kans. 67202

Filed Dec. 7, 1967, Ser. No. 9,694

Term of patent 14 years

U.S. Cl. D96—8
Int. Cl. D20—03

FIG. 1

FIG. 2

FIG. 3

FIG. 4

FIG. 5

The broken line representation of letters in FIGS. 1, 4 and 5 are for purposes of illustration only, being representation of the lettering to be used on the labels.

I claim:

The ornamental design for an embossed label card, as shown and described.
